ATTACHMENT FOR DRILL

Lester L. Meyer, Arcanum, Ohio

Application February 21, 1957, Serial No. 641,546

7. Claims. (Cl. 77—14)

This invention relates to an attachment for electric hand drills, the attachment being adapted for use in drawing a work to be drilled toward the drill, although the adaptation of the attachment is not necessarily limited to hand drills.

An object of this invention is to provide an attachment for an electric hand drill which serves, first, as a handle for supporting the drill; and, second, as a housing for an assembly for engaging the work to be drilled and for drawing the work toward the drill, which assembly may be actuated manually by an operator, with the same hand used to support the drill, to draw the work in a stepwise manner toward the drill.

Another object of this invention is to provide an attachment for a drill for drawing a work to be drilled toward the drill, wherein the attachment includes means for yieldably drawing the work toward the drill and manually operable ratchet and pawl means for positively drawing the work toward the drill in a stepwise manner.

Still another object of this invention is to provide an attachment for a drill for drawing a work to be drilled toward the drill including a cable adapted to support the work and ratchet and pawl means for actuating the cable, wherein the ratchet means to which the cable is secured is rotatably mounted so as to be rotatable with the cable.

Other objects and advantages reside in the construction of parts, the combination thereof, the method of manufacture and the mode of operation, as will become more apparent from the following description.

In the drawing

Figure 1 is a perspective view of an electric hand drill illustrating the attachment which is the subject of this invention.

Figure 2 is an elevational view with portions shown in section, illustrating the construction of the attachment and showing, in solid and broken lines, two positions of a ratchet actuating assembly associated with the attachment.

Figure 3 is an elevational view, with portions shown in section, illustrating a third position of the ratchet actuating assembly.

Referring to the drawing in detail, Figure 1 illustrates a conventional pistol grip type electric hand drill 10 to which the attachment 12, which is the subject of this invention, is attached. The attachment 12 comprises a tubular handle portion 14, an actuating lever 16, and a cable 18, which, as will be described later, may be selectively drawn into and released from the handle portion 14. The cable 18 is provided at one end with a hook 20 adapted to engage a chain 21, or the like, looped around or otherwise secured to the work 22 to be drilled. For the purposes of illustration only, the work 22 is a wooden board or a metallic bar.

As illustrated in Figure 2, the tubular handle portion 14 is provided at one end with an externally threaded portion 24 for attachment to the hand drill 10, and is provided at the other end with an internally threaded portion 26 adapted to receive a plug 28.

The handle portion is threadedly secured to the drill

2

housing, so as to extend substantially normal to the rotational axis of the drill. A cylindrical ratchet bar 30 is mounted for reciprocal axial motion in the handle portion 14. The ratchet bar 30 is provided with a plurality of annular notched portions 32 which are formed by beveling the peripheral wall of the ratchet bar at equispaced intervals. The ratchet bar 30 is rotatable within the handle portion 14.

The ratchet bar 30 is provided with an axial boring 33 which extends almost the entire length thereof. A coil spring 34 extending within the boring 33 is anchored at the inner end of the boring 33 to the ratchet bar 30 by a pin or rivet 36 which is welded, press-fitted, or otherwise secured in place. The spring 34 is anchored at the other end thereof to the plug 28 by a suitable pin or rivet 38. The construction of the spring 34 is such that when the ratchet bar 30 rests upon the plug 28, the spring is under a slight tension. As the ratchet bar 30 is pulled away from the plug 28, the tension of the spring increases, tending to draw the ratchet bar back toward the plug 28. The cable 18, secured to the end of the ratchet bar 30 opposite the spring 34, extends from the ratchet bar 30 out of the handle portion 14 through an opening in the wall thereof adjacent the threaded portion 24 at the end of the handle portion 14. The length of the cable 18 is approximately half the length of the handle portion 14.

The cable 18, in passing out of the handle portion 14, passes over a pulley 40 journaled upon a shaft 42 supported between spaced brackets or plates 44 welded to opposite sides of the handle portion 14 adjacent the threaded portion 24. These parallel plates 44 are recessed partially into the peripheral wall of the tubular handle portion 14. The actuating lever 16 is also pivotally secured to the plates 44 upon a shaft 48. This lever is adapted to be pivoted between a position parallel to and adjacent the handle portion 14, as shown in broken line detail in Figure 2, and positions antiparallel to the handle portion 14, one of which is shown in solid line detail in Figure 2. The lever 16 is rounded on the surface facing 40 away from the handle portion 14, such that an operator may conveniently grip simultaneously the handle portion 14 and lever 16.

Pivotedly secured to the lever 16 upon a shaft 50 is a pawl 52. The pawl 52 is adapted to project into the handle portion 14 through an opening provided therefor in the wall of the handle portion 14 into engagement with the ratchet bar 30. The pawl 52 when engaging the ratchet bar 30 opposes movement of the ratchet bar 30 in opposition to the spring 34. The pawl 52 is provided with a bifurcated arm portion 54 engaging the shaft 50. The bifurcated arm portion 54 straddles a hairpin spring element 56, one leg of which is nestled within the lever 16 and the other leg of which bears against the pawl 52, so as to urge the pawl 52 into antiparallel relationship to the lever 16. In operation, the spring 56 tends to urge the pawl 52 into engagement with the ratchet bar 30 and simultaneously tends to bias the lever 16 antiparallel to the handle portion 14. A second pawl 58 is pivotally secured to a U-shaped bracket member 60 welded to the handle portion 14 in spaced relation to the pawl 52. A leaf spring member 62, fixedly secured to the bracket member 60, urges the pawl 58 into engagement with the ratchet bar 30. The construction of the pawl 58, like that of the pawl 52, is such as to resist movement of the ratchet bar 30 in opposition to the spring 34.

It is to be noted that the shaft 50, supporting the pawl 52, is spaced from the shaft 48, supporting the lever 16, such that as the lever 16 is pivoted from the solid line position shown in Figure 2 to substantial parallel relation with the handle portion 14, as shown in broken line in Figure 2, the pawl 52 is caused to move axially so as

to drive the ratchet bar 30 axially in the handle portion 14 toward the plug 28. The arrangement is such that the axial movement of the pawl 52, as the lever 16 is moved manually into parallel relation with the handle portion 14, exceeds the spacing between notched portions 32 on the ratchet bar 30. As the ratchet bar 30 is driven axially by the pawl 52, the pawl 58 is caused to jump a notch on the ratchet bar and then to re-engage the ratchet bar 30. On subsequent release of the lever 16, which under the action of the spring 56 is pivoted outwardly from the handle portion 14, the pawl 52 jumps a notch on the ratchet bar 30.

Clearly, by repeated manual actuation and release of the lever 16, the ratchet bar 30 may be driven axially in the handle portion 14 toward the plug 28, thus drawing the cable 18 over the pulley 40 into the handle portion 14.

The cable 18 may be subsequently withdrawn from the handle portion 14 by operation of the following mechanism: a tongue 64 integral with the pawl 58 projects over the pawl 52. The pawl 52 is provided with an arcuate surface 66 adapted to engage the tongue 64. The pawl 52 is also provided with an arcuate surface 68 adapted to engage a lip or bead 70 formed in the wall of the handle portion 14. Ordinarily, the spring element 56 urges the lever 16 into the solid line position of Figure 2 such that the arcuate surface 66 of the pawl 52 engages and pushes against the tongue 64 of the pawl 58 and simultaneously the arcuate surface 68 of the pawl 52 engages the lip 70 associated with the handle portion 14. Clearly, the springs 56 and 62 are in opposition when the lever 16 is in this position. Due to the low mechanical advantage associated with the spring 56 in this position, however, the spring 62 prevails and urges the pawl 58 into positive engagement with the ratchet bar 30.

By manually urging the lever 16 away from the handle portion 14 to the position shown in Figure 3, the arcuate surface 68 of the pawl 52 may be caused to cam upon the lip 70 of the handle portion 14 against the tongue 64 of the pawl 58, so as to move the pawl 58 out of engagement with the ratchet bar 30 in opposition to the spring 62. By such movement of the lever 16, both pawls 52 and 58 may be caused to simultaneously disengage the ratchet bar 30. Outward movement of the lever 16 from the handle portion 14 is limited by an abutment 72 associated with the plates 44 which engages a complementary abutment 74 associated with the lever 16.

When the lever 16 is manually pivoted to this extreme antiparallel position, the cable 18 may be manually withdrawn from the handle portion 14 by grasping the hook 20 attached to the cable 18 and pulling the cable 18 in opposition to the spring 34. When the cable 18 has been withdrawn, the handle portion of the lever 16 may be returned to the intermediate non-parallel position, shown in Figure 2 in solid line detail, whereupon the pawl 58 will engage the ratchet bar 30.

The operation of the device is as follows: After actuating the lever 16 to its extreme antiparallel position with respect to the handle portion 14, as shown in Figure 3, the cable 18 may be manually withdrawn from the handle portion 14, whereupon the hook 20 may be attached to a chain or the like for supporting the work to be drilled. The spring 34, opposing withdrawal of the cable 18 from the handle portion 14, operates to draw the cable 18 back into the handle portion 14 to take up slack in the cable 18 and work engaging chain. Subsequently, the lever 16 is returned to the intermediate antiparallel position, shown in solid line detail in Figure 2, and the drill is put into operation. By manually actuating the lever 16 repeatedly, while simultaneously supporting the drill by the handle portion 14, the ratchet bar 30 may be driven axially in the handle portion 14 so as to cause the drill to penetrate the work. In this operation, the pawl 58 serves to prevent slippage of the ratchet bar 30.

So that the lever 16 may be properly oriented on the

handle portion 14 for convenient actuation while the drill is being operated, the end of the handle portion engaging the drill housing is provided with internal threads at 49 for receipt of a tapered plug 51. The depth of the plug 51 in the handle portion 14 is adjusted such that when the handle portion 14 is turned tightly into place in the drill housing, the handle portion 14 has the proper angular orientation relative to the drill housing. To facilitate adjustment and locking of the plug 51, the handle portion 14 is split at 53.

It is to be noted that the ratchet bar 30 which is rotatable in the handle portion 14 is capable of rotating with the cable 18. Thus, while the cable 18 may ordinarily tend to twist during the drilling operation and thus be subjected to harmful torsional stress, such a result is precluded in the present invention.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. An attachment for an electric hand drill including a tubular handle portion attachable at one end to the drill housing and adapted for use in holding the hand drill, a ratchet bar mounted for reciprocal axial movement in said handle portion, said handle portion having an opening in the wall thereof, a cable having one end secured to said ratchet bar passing through said opening and having the other end thereof adapted to support a work to be drilled, a lever pivotally secured to said handle portion, the construction and arrangement being such that said lever may be actuated manually by an operator with the same hand used to hold the handle portion, and pawl means responsive to pivotal movement of said lever for actuating said ratchet bar axially in said handle portion in a stepwise manner so as to draw said cable into said handle portion thereby drawing said work towards the drill.

2. The attachment according to claim 1, wherein said ratchet bar comprises a substantially cylindrical member provided with axially spaced annular notched portions adapted to be engaged by said pawl means, and wherein said ratchet bar is mounted for rotation in said handle portion.

3. The attachment according to claim 1, including spring means biasing said ratchet bar axially in said handle portion so as to exert a spring tension tending to draw said cable into said handle portion.

4. An attachment for an electric hand drill including a tubular handle portion attachable at one end to the drill housing and adapted to extend substantially normal to the axis of rotation of the drill, a ratchet bar mounted for reciprocal movement in said handle portion, said handle portion having an opening in the wall thereof, pulley means secured to said handle portion adjacent the opening therein, a cable having one end thereof secured to said ratchet bar passing out of the opening in said handle portion over the pulley means, said cable being adapted at the other end thereof to support a work to be drilled, a lever pivotally secured to said handle portion and having a first position substantially parallel to said handle portion, spring means biasing said lever into a second position antiparallel to said handle portion, the construction and arrangement being such that an operator grasping said handle portion to hold said drill may, with the same hand, actuate said lever repeatedly from said second position to said first position, and pawl means responsive to movement of said lever for actuating said ratchet bar axially in said handle portion in a stepwise manner so as to draw said cable into said handle portion

thereby drawing the work supported by said cable towards said drill.

5. The attachment according to claim 4, wherein said lever has a third position in extreme antiparallel relation to said handle portion, and including cam means responsive to movement of said lever to said third position for disengaging said pawl means from said ratchet bar, and spring means urging said ratchet bar axially in said handle portion so as to draw said cable into said handle portion when said pawl means is disengaged from 10 said ratchet bar.

6. The attachment according to claim 4, wherein said ratchet bar comprises a substantially cylindrical member provided with axially spaced annular notched portions adapted to be engaged by said pawl means, and wherein 15 said ratchet bar is mounted for rotation in said handle portion.

7. The attachment according to claim 4, wherein the

end of the handle portion attachable to the drill housing is provided with an externally threaded portion for threadedly engaging the housing and an internally threaded portion, and including a tapered plug threadedly engaging said internally threaded portion so as to adjustably engage said handle portion, the construction and arrangement being such that said plug may be adjusted to enable positioning of said handle portion in a predetermined angular relation to said housing, said handle portion having a split portion in the end thereof receiving said plug providing a spring tension for locking said plug in position.
